DEVICE FOR TYING WIRE AROUND AN ARTICLE

Anton Gubser, Riedern, and Anton Broder,
Sargans, SwitzerlandApplication February 10, 1944, Serial No. 521,882
In Switzerland January 30, 1943

2 Claims. (Cl. 81—9.3)

1

This invention relates to a device for tensioning and securing pieces of binding wire which are initially in U-shaped pieces and which are shaped into a ring by pulling the free ends through the bent or loop portion of the U. The shanks of a wire are applied to the article that is to be tied and are bent back against the wire loop so as to secure the binding wire on the article, for which purpose a number of tensioning arrangements have already been proposed which, during manipulation, require their front end to be applied to the wire loop of the binding wire. In order to be able to draw the binding wire as tightly as possible, a small wire loop must be employed, and also it must be possible to equalize the pull on the two wire ends.

In order adequately to fulfill the aforesaid conditions, the tensioning device of the present invention differs from previously known arrangements by providing a front stem shaft portion which at its forwardly tapered head end has two diametrically opposite longitudinal grooves for receiving the two wire ends, said front portion being longitudinally adjustable from a rear shaft portion to which a two-armed tensioning lever is pivoted for limited movement, the two arms of which are each provided with a clamping means for holding the wire ends.

This, on the one hand, even if the binding wire has only a small loop, makes it possible to apply the tensioning device to the wire loop in more positive fashion inasmuch as the front shaft portion is suitably guided on the wire ends spread along its longitudinal ends, whereas, on the other hand, due to the limited pivotal movement of the tensioning lever, it is possible to equalize the pull on the wire ends so that both wire ends will be uniformly drawn up. It is therefore possible by using binding wire of suitable length also to wind this in supplementary fashion around the article that is to be tied.

Fig. 1 shows the tensioning device in position of use in an axial section through the stem;

Fig. 2 is a top plan view of Fig. 1;

Fig. 3 shows a cross section on the line III—III in Fig. 1;

Figs. 4 and 5 illustrate two different working phases in effecting the tie;

Fig. 6 is a perspective view of the thus effected tie, and

Fig. 7 shows the same kind of a tie for a different use.

The tensioning device is provided with a cylindrical stem composed of two telescopically connected parts 1 and 2. The rear stem part 2 car-

ries a tensioning screw 3 serving as an abutment for the front stem part 1 which is provided with a longitudinal slot 4 for the passage of a pin 5, which is transversely arranged on the stem part

5. On the end portions of this pin a two-armed lever 6 is mounted which surrounds the stem. The lever 6 is provided with an oblong opening 7 for allowing limited pivotal movement of this lever relative to the stem about the bearing pin 5.

10 Each arm of the lever 6 is provided with a hole 8 with which a clamping screw 9 is associated. The front stem part 1 has on its outer end a conical taper and is provided within the embrace of this taper with two diametrically opposed longitudinal grooves 10.

15 For the purpose of carrying out the method according to this invention a piece of wire of sufficient length is cut off of the supply wire of an appropriate thickness.

20 This wire piece is bent double into U-shape, as shown in Fig. 4, which can be done, for example, with the aid of a template. The wire work blank thus formed is then brought into the form of a ring and its two shanks 11 are pulled through the loop 12 formed in the wire work blank.

25 This operation is carried into effect dependent upon circumstances either directly on the receiving object or on a suitable support, particularly if the wire is of considerable thickness.

30 Otherwise the shaping of the ring may also be effected by hand exclusively.

35 As shown in Fig. 5, the wire work blank is formed into a rectangular ring 13 in adaptation to its use consisting, for example, in providing a tie about a beam 14 which on its backside has a longitudinal fissure (as indicated in Fig. 2), as a defect liable to end in failure. It will be understood that the wire work blank can in most simple manner be formed into a rectangular ring directly on the beam 14.

40 After the ring 13 has been arranged on the beam 14 and the tensioning device applied to the ring, the wire shanks 11 are spread apart and separately inserted in the longitudinal grooves

45 10 of the front stem part 1 and introduced into the holes 8 in the lever 6 and clamped fast to this lever by means of the clamping screws 9. Thereupon, the tensioning screw 3 is turned in the proper direction to displace the rear stem part 2 axially along the circumference of the stem part 1 backwardly, the latter part abutting against the wire ring 13, that is, the beam 14.

The bearing pin 5 for the lever 6 shares in this displacing movement, whereby the wire shanks 55 11 are tensioned by means of the lever 6, in con-

sequence whereof the wire ring 13 is tautened against the beam 14 so as to closely draw to it more and more of the wire and eventually engages the beam with a snug fit. Due to the fact that the lever 6 engaging with the two wire shanks 11 is pivotally mounted on pin 5, the effect of tensile load on the two wire shanks, which is initially unequal in most cases, is equalized.

After the wire ring 13 has then been tightened upon the beam 14 in the required manner the two wire shanks 11 are bent backward at the yoke 12 of the wire loop in the corresponding direction of tensioning by appropriately tilting the stem 1, 2 about the bearing point presented to it by the beam 14. Thereupon the wire shanks 11 are released from engagement with the lever 6 so that the tensioning device can be removed, whereupon the wire shanks 11 are cut off to appropriate length permitting the formation of closed eyelets with the wire ends by driving said ends inward to some extent for example, with a hammer, in which way a secure closure is obtained, as shown in Fig. 6. The longitudinal grooves 10 arranged in the conically tapering free end of the front stem portion 1 of the tensioning device for the reception of the spreading wire shanks 11 guide these shanks safely in a manner to facilitate their tautening.

As shown in Fig. 7, the wire ring 13 effected in the precedingly described fashion is well suited for forming a solid tie between a rubber hose 15 and a tubular metal piece 16. On the free end of the piece 16 a second rubber hose may be pushed and fixed by means of a wire ring to the piece 16 in a manner similar to the fixing of the rubber hose 15, so that it is possible to unite two rubber hoses with each other into a conduit by means of a tubular piece.

Obviously, various further examples of practical application of binding wire in accordance with the invention could be given.

We claim:

1. A wire-tensioning device comprising a stem composed of two telescopic parts, a screw for forcibly moving one of said parts axially with respect to the other, one of said parts having a tapered outer end provided with a pair of oppositely disposed wire accommodating grooves, said one part having a longitudinally extending transverse slot, a pin extending through said slot and through the other portion of said stem whereby the pin is free to move axially with respect to the

stem part having the tapered end, a two-armed lever pivotally mounted on said pin, and means in the ends of said lever equidistant from the axis of the pin for clamping the shanks of the wire, whereby when the means for forcing the parts of the stem is actuated the shanks of wire are drawn through the loop of wire with equal tension, regardless of difference in length of the two shanks of the loop.

2. A device for tensioning and securing binding wire formed in pieces bent double in U-shape comprising, a shaft composed of a front portion and a rear portion, means for adjusting the front and rear portions of the shaft longitudinally, the front portion being tapered toward its front end and being provided adjacent said end with two oppositely located longitudinally extending grooves adapted for receiving and guiding the shanks of the U-shaped binding wire when said shanks are drawn through the loop formed at the bent portion of the wire in forming a binding, a two-armed lever, pivot means pivotally securing the lever to the rear portion of the shaft with the arms extending generally transversely of the axis of the shaft and lying in a plane generally transverse of the plane of the loop, said lever being swingable about its pivot in a plane extending longitudinally of and including the axis of the shaft, and means for clamping a wire shank on each of the lever arms at equal distances from the axis of pivoting.
